UNITED STATES PATENT OFFICE.

JOHN J. TATUM, OF BALTIMORE, MARYLAND.

DRAFT-RIGGING.

1,279,176.

Specification of Letters Patent. Patented Sept. 17, 1918.

Application filed June 24, 1913. Serial No. 775,508.

To all whom it may concern:

Be it known that I, JOHN J. TATUM, a citizen of the United States, residing in the city of Baltimore and State of Maryland, 5 have invented certain new and useful Improvements in Draft-Rigging, of which the following is a specification.

This application was filed as a continuation of my application filed July 30, 1909, 10 Serial No. 510,406, as to all matters common to the two applications.

One of the objects of my invention is to provide a yoke head for a draft gear provided with transverse slots, said head to receive a coupler and said slots to receive a coupler key.

Another object of my invention is to provide a draft gear yoke with an extension connected thereto for radial movement and 20 forming a receptacle for the reception of the rear end of a draw or coupler bar, said receptacle having elongated keyways and said bar having a keyway registering with said slots and a cross key through said keyways 25 to lock the bar in said receptacle, whereby the receptacle or yoke head swings radially with the bar; and with these and minor objects in view, my invention consists of the parts and combination of parts as will be 30 more fully hereinafter pointed out.

In the drawing—

Figure 1 is a perspective view of a draft gear yoke provided with a yoke head illustrative of my invention; 35 Fig. 2 is a similar view showing a coupler bar keyed to said head;

Fig. 3 is a top plan view of Fig. 2, in which the arrows indicate the direction of the radial swing of the head with the draw 40 bar.

The reference numeral 1 designates a draft gear yoke comprising a top member 1^a, a bottom member 2, and a rear member 3 constituting a yoke or casing to surround 45 shock absorbing draft devices (not shown), and having at its forward ends a bearing or stop 4. Any approved shock absorbing device, either spring or friction, may be used in connection with my invention.

50 The yoke head or receptacle 5 is loosely and swingingly mounted in the yoke and held therein by means of the stop 4 against displacement, and for the purpose of illustrating my invention, I have shown the head 55 in Fig. 1 as consisting of a band-like construction, the side walls of which are pro-

vided with elongated keyways 6, through which a cross key 7 passes. 8 is a coupler or draw bar of any approved type, the rear end of which is passed into said band-like 60 head, said end of the bar being provided with a keyway which registers with the elongated keyways 6 of the head when it is in proper position in said head, said cross key 7 passing through the said keyways to lock 65 the said draw bar to said receptacle or head, whereby the receptacle or head swings radially with the draw bar without imposing strain or stress on the draft rigging, or on the car. Further, by the employment of my 70 invention I am enabled to reduce to a minimum train resistance and to haul longer trains and greater tonnage with a minimum locomotive energy and fuel consumption.

I am enabled also to reduce rail wear, 75 wheel flange wear, thereby giving a greater factor of safety to both life and property.

The swinging head provides a flexible carrier or mounting between the draw bar and draft gear and underframing of the car, 80 which enables a train to pass the sharpest curves without reducing the engaging surfaces between the yoke and draw bar, and without imposing a shearing strain on the flange of the wheel and also enables me to 85 maintain a uniform bearing on the cross key in the slots in the head.

My invention may be applied to many types of existing draft gears and draw bars without changing the construction thereof; 90 therefore, a railroad may adopt my invention without discarding its standard type of draw bar and draft gear, it being necessary only to pivotally or swingingly mount the hood or head on the forward end of the 95 yoke or casing of the draft gear.

As will readily be seen, when a train equipped with my improved swinging head is pulling around a curve, the cross key is bearing on the front of the slots on both 100 sides of the head.

What I claim is:—

1. In a draft rigging, the combination with a draw bar having a transverse key slot through its butt end, of a yoke having a 105 front, rear, top and bottom member, a substantially U shaped loop loosely confined in said yoke, the arms of said loop each having a key slot to align with the key slot in the draw bar when the butt end of the bar is 110 spaced from the front member of the yoke, and a single key passing through said slots

and connecting the said loop to said bar; whereby the loop is free to swing laterally and move axially relatively to the yoke to accommodate the service movements of the 5 coupler.

2. A yoke for draft gear comprising a front, rear, top and bottom member, in combination with a U shaped loop loosely confined between said members, and connected 10 to a coupler bar, whereby said loop is free to swing laterally and move axially relatively to the yoke to accommodate the service movements of the coupler, the arms of said loop each having a key slot.
- 15 3. The combination with a coupler having a transverse key slot through its butt end, of a yoke for a draft gear comprising a continuous member having a space for a cushion, a member having forwardly extending arms 20 mounted to swing on the forward end of said yoke and to move axially of the yoke to accommodate service movements of the

coupler, said arms each having a key slot, and a single key passing through said slots to connect the coupler to said arms. 25

4. In a draft gear, the combination with a yoke, a member having forwardly extending arms swingingly mounted on the forward end of the yoke for radial and axial movement relatively to the yoke, said arms having a key slot, a draw bar the inner end of which projects between said arms and is provided with a key slot, a key constructed to pass through said slot in the bar and arms and secure said bar to said arms, whereby the said arms will swing radially and move axially with the draw bar in service movements. 30 35

In testimony whereof I affix my signature in presence of two witnesses.

JOHN J. TATUM.
